CLAIM

The ornamental design for smart electric pump, as shown and described.

DESCRIPTION

FIG. 1 is a front, left and top perspective view of a smart electric pump showing my new design according to a first embodiment;

FIG. 2 is rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left and top perspective view of a smart electric pump showing my new design according to a first embodiment;

FIG. 10 is rear, right and bottom perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof; and,

FIG. 16 is a bottom plan view thereof.

The broken lines depict portions of the smart electric pump that form no part of the claimed design.
